UNITED STATES PATENT OFFICE

161,004

TABLE LOBSTER TOOL

Earl F. Cook, Marblehead, Mass.

Application April 3, 1947, Serial No. 138,139

Term of patent 7 years

(Cl. D44—4)

To all whom it may concern:

Be it known that I, Earl F. Cook, citizen of the United States, residing at 4 Washington Square, Marblehead, in the county of Essex and State of Massachusetts, have invented a new, original, and ornamental Design for a Table Lobster Tool, of which the following is a specification, reference being had to the accompanying drawing, forming part thereof.

The figure is a perspective view of a table lobster tool, showing my new design.

I claim:

The ornamental design for a table lobster tool, as shown.

EARL F. COOK.
